US00D562590S

(12) **United States Design Patent** (10) **Patent No.:** **US D562,590 S**
(45) **Date of Patent:** **** Feb. 26, 2008**

(54) **DISPLAY RACK**

(75) Inventors: **Maria Alejandra Noble Colin**, Del Magdalena Contreras (MX); **Juan Manuel Avila Barriga**, Mexico City (MX)

(73) Assignee: **Sabritas, S. de R.L. de C.V.**, Col. Bosques de las Lomas Mexico City

(**) Term: **14 Years**

(21) Appl. No.: **29/248,931**

(22) Filed: **Sep. 11, 2006**

Related U.S. Application Data

(63) Continuation-in-part of application No. 11/461,659, filed on Aug. 1, 2006.

(51) **LOC (8) Cl.** **06-04**

(52) **U.S. Cl.** **D6/462**

(58) **Field of Classification Search** D6/408, D6/407, 462-465, 515, 512, 552, 458-460; 211/90.03, 112, 90.04, 113, 181.1, 189, 198, 211/55, 50, 49.1, 106, 184, 59.2, 134; 248/51

See application file for complete search history.
